UNITED STATES PATENT OFFICE

NOEL J. POUX, OF MEADVILLE, PENNSYLVANIA, ASSIGNOR TO LION FASTENER INC.,
OF MEADVILLE, PENNSYLVANIA, A CORPORATION OF DELAWARE

SEPARABLE FASTENER

Application filed June 6, 1930. Serial No. 459,456.

In forming separable fasteners involving adjacent edge to edge stringers provided with interlocking members it has been common to secure the stringers at the end of the interlocking members with a metallic plate. The present invention is designed to improve this manner of securing the ends of the working portion of the fastener together by a scheme of cross stitching which secures the stringers together securely and forms an abutment, or stop limiting the movement of the common operating slider. Features and details of the invention will appear from the specification and claims.

A preferred embodiment of the invention is illustrated in the accompanying drawings as follows:

- Fig. 1 shows a plan view of the fastener having the stitched end closure.
- Fig. 2 a section on the line 2—2 in Fig. 1.
- Fig. 2a a central section through the slider.
- Fig. 2b an enlarged section on the line 2—2 showing the end of the stitching.
- Fig. 3 a side elevation of the structure shown in Fig. 1.
- Fig. 4 a view similar to Fig. 1 indicating a modified stop plate at the end of the interlocking fasteners.
- Fig. 5 a section on the line 5—5 in Fig. 4.
- Fig. 6 an edge view of the structure shown in Fig. 4.
- Fig. 7 an edge view of a stop plate.
- Fig. 8 an elevation of the stop plate shown in Fig. 4.
- Fig. 9 a modification of the structure shown in Fig. 1 involving additional longitudinal stitches at the end of the interlocking members.
- Fig. 10 a section on the line 10—10 in Fig. 9.
- Fig. 11 an elevation of the stop plate shown in Fig. 9.
- Fig. 12 an edge view of the same.

Fig. 13 a plan view of a modification from that shown in Fig. 1.

Fig. 14 an edge view of the same.

Stringers 1 have the usual ribs 2 along their adjacent edges. Interlocking members 4 are arranged in staggered opposing series on the opposite ribs 2, these members being provided with the usual jaws 5 which are closed into clamping engagement on these ribs. The interlocking members have 50 projections 6 and cavities 7, the projections on the interlocking members at one edge extending into the cavities of the members on the opposite edge to form the lock between the members. A slider 8 is provided with the usual guide flanges 9 and the separating arrow-shaped center 10, this slider operating with relation to the interlocking members swinging them into and 60 out of interlocking engagement. The slider 65 is provided with the usual loop 11 and tag 12 by means of which the slider is operated. So far the parts are of common construction.

A closure at the end of the interlocking members is formed by a series of rows of cross stitching 13, this stitching being preferably formed by long cross stitches embracing both ribs, the threads at the top and bottom being preferably connected by locks 70 14 in the manner of the ordinary lock stitching. A longitudinal line of stitching 15 is preferably provided along the dividing line between the ribs drawing the cross stitches down into close binding engagement with the ribs. This stitching in itself acting with the slider makes a very desirable stop for the slider in that the last two interlocking members are held together as the slider does not move down far enough to separate them. Consequently with each operation of the fastener the opposing series of the members are sure to be in proper relation to be swung into engagement.

I prefer to form stops 26 for the slider 90

at the open end of the fastener. These stops are formed in a manner similar to the cross stitching 13 except the cross stitching is around one rib and extends through the fabric back of the rib. The cross stitching may involve more than one thickness of stitching. When the slider reaches the closing limit it contacts these masses of stitching and is thus stopped.

- 10 In the modified construction shown in Figs. 4 to 8, the parts and stitching is similar to that shown in Fig. 1, but a stop plate 16 is arranged between the edges at the end of the stitching. The plate 16 has forked 15 ends 17 straddling the ribs and these forked ends are adapted to engage the guide ribs 9 of the slider and form a stop therefor.

In the structure shown in Fig. 9 there is added to the cross stitches 13, as shown in 20 Fig. 1, a series of longitudinal stitches 19 embracing the cross stitches and at the stop end of the cross stitches. The modification also involves a stop plate 20 having forked ends 21 adapted to straddle the edges of the 25 stringers and provided with projections 22 which are adapted to engage the top and bottom walls of the slider.

In Figs. 13 and 14 I have shown a modification in which there is placed between the 30 ribs 2, 2, a spacing filler 23 and a cross stitching 24 extends back and forth in parallel lines embracing the ribs 2, 2, as well as the interposed filler 23. Two lines of longitudinal stitching 25 embrace the 35 cross stitches, these lines of stitches being between the edges and the interposed filler.

What I claim as new is:—

1. In a separable fastener, the combination 40 of stringers having opposing series of interlocking members on the stringers adapted to be swung into and out of locking engagement; a slider operating the members; and a sewed connection between the edges at the ends of the series of members 45 forming a connection for the stringers and forming a means for limiting the movement of the slider with the slider in position to actuate the end members.

2. In a separable fastener, the combination 50 of stringers having opposing series of interlocking members on the stringers adapted to be swung into and out of locking engagement; a slider operating the members; and a sewed connection between the 55 edges at the end of the series of members forming a connection for the stringers and forming means for limiting the movement of the slider with the slider in position to actuate the end members comprising a series 60 of parallel cross stitches extending from edge to edge.

3. In a separable fastener, the combination 65 of stringers having opposing series of interlocking members on the stringers adapted to be swung into and out of locking

engagement; a slider operating the members; and a sewed connection between the edges at the end of the series of members forming a connection for the stringers and forming a means for limiting the movement 70 of the slider with the slider in position to actuate the end members comprising a series of parallel cross stitches extending from edge to edge and longitudinal stitches embracing the cross stitches.

4. In a separable fastener, the combination 75 of stringers having opposing series of interlocking members on the stringers adapted to be swung into and out of locking engagement; a slider operating the members; and a sewed connection between the edges at the end of the series of members forming a connection for the stringers and forming a means for limiting the movement 80 of the slider with the slider in position to actuate the end members comprising a series of parallel cross stitches extending from edge to edge and longitudinal stitches embracing the cross stitches between the edges 85 of the stringers.

5. In a separable fastener, the combination 90 of stringers having opposing edges provided with ribs; opposing series of interlocking members on the stringers engaging said ribs and adapted to be swung into and out of locking engagement; a slider operating the members; and a sewed connection 95 embracing the ribs at the ends of the members connecting the stringers and forming a means for limiting the movement 100 of the slider.

6. In a separable fastener, the combination 105 of stringers having opposing edges provided with ribs; opposing series of interlocking members on the stringers engaging said ribs and adapted to be swung into and out of locking engagement; a slider operating the members; and a sewed connection 110 embracing the ribs at the ends of the members connecting the stringers and forming a means for limiting the movement of the slider comprising a series of parallel cross stitches extending over the ribs.

7. In a separable fastener, the combination 115 of stringers having opposing edges provided with ribs; opposing series of interlocking members on the stringers engaging said ribs and adapted to be swung into and out of locking engagement; a slider operating the members; and a sewed connection 120 embracing the ribs at the ends of the members connecting the stringers and forming a means for limiting the movement of the slider comprising a series of parallel cross stitches extending over the ribs and longitudinal stitches embracing the cross stitches 125 and extending between the ribs.

8. In a separable fastener, the combination 130 of stringers having opposing series of interlocking members on the stringers

adapted to be swung into and out of locking engagement; a slider operating the members; and a sewed connection between the edges at the end of the series of members forming a connection for the stringers; and a stop plate between the edges backed by the stitching, said stop plate limiting the movement of the slider.

9. In a separable fastener, the combination of stringers having opposing series of interlocking members on the stringers adapted to be swung into and out of locking engagement; a slider operating the members; and a sewed connection between the edges at the end of the series of members forming a connection for the stringers; and a stop plate between the edges backed by the stitching, said stop plate limiting the movement of the slider and having forked ends straddling the edges of the stringers.

10. In a separable fastener, the combination of stringers having opposing series of interlocking members on the stringers adapted to be swung into and out of locking engagement; a slider operating the members; and a sewed connection between the edges at the end of the series of members forming a connection for the stringers and forming a means for limiting the movement of the slider with the slider in position to actuate the end members comprising a series of parallel cross stitches extending from edge to edge and a series of longitudinal stitches extending from side to side of the cross stitches.

11. In a separable fastener, the combination of stringers having opposing interlocking members on the stringers adapted to swing into and out of locking engagement; a slider operating the members; and a stop for the slider formed of a mass of stitching in the stringers.

12. In a separable fastener, the combination of stringers having opposing interlocking members on the stringers adapted to swing into and out of locking engagement; a slider operating the members; and a stop for the slider formed of a mass of cross stitching in the stringers.

13. In a separable fastener, the combination of stringers having opposing interlocking members on the stringers adapted to swing into and out of locking engagement, the stringers being united at one end of the line of interlocking members and open at the opposite end; a slider operating the members; and a stop at the open end of the stringers formed of a mass of stitching in one of the stringers.

14. In a separable fastener, the combination of stringers having opposing interlocking members on the stringers adapted to swing into and out of locking engagement; a slider operating the members; and stops for the slider at both ends of the members

formed of masses of stitchings in the stringers.

15. In a separable fastener, the combination of stringers formed with ribbed edges and having opposing interlocking members on the stringers adapted to be swung into and out of locking engagement, the stringers being united at one end of the line of interlocking members and open at the opposite end; a slider operating the members; and a stop for the slider at the open end of the stringers formed of a mass of cross stitches extending over the ribbed edge of one of the stringers.

In testimony whereof I have hereunto set my hand.

NOEL J. POUX.
